UNITED STATES PATENT OFFICE.

THOMAS J. SANDS, OF PROVIDENCE, RHODE ISLAND, ASSIGNOR TO UNIVERSAL WINDING COMPANY, OF PORTLAND, MAINE, A CORPORATION OF MAINE.

SKEIN-UNWINDING DEVICE.

1,085,360.

Specification of Letters Patent.

Patented Jan. 27, 1914.

Application filed December 2, 1912. Serial No. 734,576.

To all whom it may concern:

Be it known that I, THOMAS J. SANDS, a citizen of the United States, residing at Providence, in the county of Providence and 5 State of Rhode Island, have invented certain new and useful Improvements in Skein-Unwinding Devices, of which the following is a specification.

My invention relates to unwinding devices 10 for controlling the unwinding of yarn or thread from hanks or skeins, in delivering the same to winding or other textile machines.

My improvement consists essentially in 15 providing means influenced by the tension of draft on the yarn and adapted to act directly on the skein to regulate the unwinding of the strands.

The object of my improvement is to accomplish a more sensitive and direct control 20 of the unwinding or unreeling of the yarn so as to prevent strain or breakage of the individual strands and, furthermore, to facilitate the delivery of the yarn by lessening its 25 tendency to become tangled or caught in the skein. By arranging the controlling devices to act directly on the skein instead of on the swift, reel, runner or other device which supports it, I avoid the effects of the momentum 30 and inertia of these parts and consequently relieve the yarn of the strain to which it is usually subjected by being obliged to operate the braking mechanism employed in connection with the rotating elements.

The invention is fully explained in the 35 following specification, illustrated by the accompanying drawings, in which:

Figure 1 is a side elevation of my new device showing it applied to a usual form of 40 winding machine; Fig. 2, a plan view of the upper skein-holder or runner and its supporting devices, showing the arrangement of the tension controller-arm in connection therewith; Fig. 3, a plan view of the lower 45 runner and its supporting devices; Figs. 4, 5 and 6, enlarged views showing details of construction.

Referring first to Fig. 1, A designates the

frame of a winding machine of well known construction which is mounted on a bed B 50 supported by uprights or legs C. The machine of the style here shown is generally made up of a number of frames or heads A arranged in series along the bed B and carrying bearings for the winding-spindles d 55 which project from the sides thereof. Suitable brackets E also overhang the sides of the frames A and serve as supports for the reciprocating thread-guides e which are traversed along the winding-spindles to deposit 60 the thread or yarn thereon to form the cops or bobbins as illustrated at X. It is to be understood, however, that my new unwinding device is applicable to winding machines of other types than that here shown and is 65 adapted for use with various and sundry apparatus employed in the manufacture of textiles.

I have preferred to illustrate my invention as arranged to be applied to the winding 70 machine in series, corresponding to the arrangement of the series of winding-spindles, but only one complete device is here shown since all of them are usually of the same construction.

For supporting the devices on the machine I employ two parallel, horizontal rods or bars F, F' which are preferably square or rectangular in cross-section and arranged to be held in brackets, G, G'. The brackets G, 80 G' consist of opposite jaw-members g, g' adapted to be clamped over the flanges e of the legs C by means of the bolts g², as shown more particularly in Figs. 2 and 3. The main jaw-member g is formed with an upwardly extending bearing g³ and a depending tail-piece g⁴ adapted to bear against the side of the leg C to take the downward thrust due to the weight of the parts supported on the brackets. Extending through 85 the bore of the bearing g³ is a sleeve or bushing H formed with a square or rectangular hole adapted to receive the rod F or F'. The rods F and F' are held in the sleeves H by the set-screws h and the sleeves, in turn, 90 are held in the bearings g³ by set-screws h'. 95

The screws h' are preferably formed with rounded or pointed ends adapted to engage correspondingly formed circumferential grooves h^2 cut in the peripheries of the sleeves H. This arrangement serves to hold the sleeves longitudinally of the bearings g^3 while providing for a firmer grip of the screws to prevent accidental turning of the sleeves. By loosening the screws h' slightly the sleeves can be turned in their bearings g^3 to adjust the rods F, F' about their axes and thereby alter the position of the arms J, J' which are supported on the rods.

15 The arms J and J' support the rotatable reels or runners K and K' around which the skein Y is stretched. The upper arm J is formed at its inner end with a hub j having a square or rectangular slot on its under side adapted to receive the rod F. The arm is thus prevented from turning on the rod, but can be slid longitudinally thereof to adjust its position along the machine and a set-screw j' serves to secure the arm in its proper position. Midway between its extremities, the arm J is formed with a downwardly extending crook or elbow j^2 provided with a hub j^3 in which is secured a horizontal rod L by means of the set-screw l . Preferably, 30 the rod L extends outward from both sides of the arm J to provide bearings for a pair of runners K, only one of them being shown in the drawings. These runners or reels K operate with a pair of similar runners K' arranged below on the arm J' and together 35 serve to support the skeins which deliver to two adjacent winding-spindles on the frame A.

Pivoted on the rod L adjacent the end of 40 the hub j^3 is a block M, shown in detail in Figs. 4 and 5, which carries the wire controller-arm N for controlling the unwinding of the skein. The block M is formed with a vertically extending slot m , and the wire 45 arm N rests in the bottom of this slot. A bowed spring-plate O, having its body portion fitted to the slot and laterally-projecting ears o, o abutting the ends of the block M to keep it in position therein, is arranged 50 above the arm N with its extremities engaging the latter. Screwed into the top of the block M is a set-screw p adapted to be set down against the spring-plate O to bind it against the arm N and hold the latter in 55 position in the slot m . By releasing the screw p the arm N can be moved longitudinally in the block M to adjust it in relation to the skein, as afterward more particularly described. The outer end of the arm N is 60 formed with an eye or "pigtail" n through which the yarn y is adapted to draw as it leads from the skein Y, while its inner end is bent into a fork or loop n' adapted to inclose the strands of the skein on its under

side, as shown in Fig. 1. The rear cross-bar 65 of the fork n' is of substantially V-shape for a purpose hereinafter explained.

Extending through a lug j^4 at the outer end of the arm J is a right-angled elbow-member R, adapted to slide to adjust its upright arm r toward or away from the axis of the arm N, and secured in position by the set-screw r' . A U-shaped clamp r^2 is arranged to be adjusted vertically on the arm r of the member R and is held in position by the set-screw r^3 . A helical spring S is secured at one end to the clamp r^2 with its opposite end fastened to a clamp s , the latter being clamped on the arm N by means of a screw s' .

80 The reels or runners K, K' may be of any usual form, but as here shown consist of circular end-flanges k, k , with cross-bars or struts k' extending between them. The upper runner K is supported rotatively on the rod L, as previously explained, with its inner flange abutting the end of the block M and is held in place by the collar l' secured on the rod by a set-screw l^2 . The lower runner K' is mounted to rotate on the right-angled extension t of a wire arm T and is held in position by the collars t', t' which are secured to the rod by set-screws t^2, t^2 . The arm T is supported at the end of the arm J', which latter is secured to the lower 95 rod F' in the same manner as the upper arm J.

90 Referring to Figs. 1 and 6, the arm T is held in an adjustable bearing-member U which is pivoted on a rod u extending 100 through a hub j^5 at the end of the arm J' and secured in place by the set-screw j^6 . A collar j^7 secured by the set-screw j^8 serves to retain the bearing-member U in place on the rod u . The member U is formed with a hub u' , see Fig. 6, in which is a split bushing u^2 through which the arm T extends. A set-screw u^3 in the member U has its end formed with a reduced portion u^4 which engages a radial hole u^5 in the bushing u^2 to hold the latter in the hub u' . The screw u^3 is adapted to be set against the bushing u^2 to bind it on the arm T and by loosening the screw u^3 the arm T can be slid in the member U to 110 adjust the position of the runner K' in relation to the pivot point of the arm.

115 Adapted to slide on the rear end of the arm T is a weight V, held in position by the set-screw v and arranged to counterbalance the weight of the runner K'. A lug j^9 projects from the side of the arm J' and is adapted to contact with the arm T to prevent its forward end from tilting downward beyond a substantially horizontal position.

120 The complete device operates as follows: 125 The skein Y is stretched around the cross-bars of the two reels or runners K, K', the runner K' being swung upward on its arm

T to facilitate the placing of the skein over the heads or flanges k. The arm T is then adjusted in the bearing-member U so that the skein will be kept taut by the weight of the runner K' while the arm is in a substantially horizontal position. The weight V is then set to partly counterbalance the runner according to the character of the material in the skein. For use with very light, 10 fine yarns the weight V is set so that it very nearly balances the weight of the runner; but for very heavy, coarse yarns more tension is required to stretch and straighten the strands so that the weight V is moved 15 toward the pivot point of the arm T, and, under extreme conditions, can even be placed on the same side of the pivot with the runner itself. To adapt the device to different lengths of skeins the arm J' can be swung 20 upward or downward, to regulate the distance between the runners, by simply turning the rod F' in its bearings in the brackets G'; it being understood that there are two brackets for supporting the rod F', one at 25 either end of the machine. This is accomplished by loosening the set-screws h' to allow the sleeves H to turn in the bearings g', as before described. Where extreme 30 changes in the relative position of the runners are necessary the brackets G and G' can be moved upward and downward on the legs C. The single strand of yarn y is drawn from the top of the skein Y and carried through the pigtail n at the end of the controller-arm N. Thence it is carried up over 35 a guide-pulley w on the end of a compensator-arm W and led to the winding-spindle d after being threaded through the thread-guide e. The compensator-arm W is controlled by a spring w' to keep the yarn taut 40 and is usually arranged to cause the operation of the stopping-mechanism of the machine when the yarn breaks or is exhausted, but as these devices form no part of the 45 present invention, they have not been described in detail. The fork n' at the rear end of the controller-arm N reaches under and incloses the strands of the skein Y and is pressed against the yarn through the effect 50 of the spring S. Before the machine is started the elbow-member R is adjusted to give the proper tension to the spring S to maintain the proper contact of the fork with the skein and this pressure is automatically varied during the unwinding of the yarn through the operation of the arm N. The point of connection of the spring S can also be adjusted along the arm N to vary the leverage exerted thereon. The position of the fork n' in relation to the skein is adjusted by swinging the arm J upward or downward, this being effected by 55 turning the rod F in its bearings in the bracket G. When the winding-spindle first

starts to rotate the yarn will be taken up 65 with a sudden draft and its pull on the arm N will cause the latter to be rocked to entirely remove the fork n' from contact with the skein Y and allow the latter to move freely. After this first sudden pull, the 70 tension of the draft will be relieved and the arm N will be moved by the spring S to carry the fork n' into engagement with the skein once more to prevent a too free movement of the latter on the rotating runners 75 K and K'. In this way the tension of draft on the delivering yarn serves to regulate the pressure of the fork n' against the skein and provides an inductive control which prevents the yarn from delivering too freely 80 while, at the same time, facilitating its unwinding. The V-shaped construction of the cross-bar of the fork n' is designed to adapt it to conform to the natural contour of the outside of the skein Y, as illustrated by the 85 dot-and-dash lines in Fig. 2, and it has been demonstrated that the action of this fork is to gather the skein somewhat as it is gathered in the hand when being stretched and straightened. That is to say, the fork n' has an action 90 which tends to straighten and aline the strands of the skein and to keep them in position to deliver freely without tangling or snarling. When the skein is allowed to flatten out over the reels or runners on 95 which it is supported the coils become crossed and misplaced so that the delivery of the yarn is impeded. With my improved device the yarn is maintained with the coils more nearly in their proper parallelism and 100 the intermittent gathering action of the fork n' serves to loosen and free them one from another, so that the yarn pulls off more easily.

It will be noted that in my new device 105 there are no braking elements acting on the runners to control their rotation and for this reason the runners can be made of very light construction so as to avoid the effects of inertia and momentum. For this reason, 110 that is, owing to their light weight, the rotation of the runners can be started much more easily and therefore less strain is put upon the yarn. Furthermore, when the draft on the yarn is arrested at the stopping 115 of the winding, there will be less tendency for the runners to run ahead owing to momentum and unwind a length of yarn not required. The yarn is also relieved of the strain which would arise from causing it to 120 operate braking devices for the runners.

My new device is adapted for universal adjustment for all lengths of skeins and for all sizes and weights of materials. It can be employed to unwind the finest silk without 125 subjecting the material to undue strain or stress, and is equally well adapted for coarse or heavy yarns.

4

Various modifications might be made in the form and structure of the parts of my device without departing from the spirit or scope of the invention.

5 Therefore, without limiting myself to the exact arrangement shown, what I claim is:—

1. In a skein-unwinding device, the combination with spaced-apart rotatable supports for holding a skein stretched between 10 the same, of a controller-arm adapted to be operated from the tension of draft on the delivering yarn to apply pressure to the free length of skein extending between the supports to control the unwinding of the strands thereof.

2. In a skein-unwinding device, the combination with spaced-apart rotatable supports for holding a skein stretched between 20 the same, of a controller-arm pivoted adjacent said supports and arranged to be operated by the tension of the delivering yarn, said arm having one end adapted to bear directly against the free length of skein extending between the supports to control the 25 unwinding of the strands thereof.

3. In a skein-unwinding device, the combination with spaced-apart rotatable supports for holding a skein stretched between 30 the same, of a controller-arm pivoted adjacent said supports and carrying a guide at one end through which the strand of yarn draws, said arm arranged with its opposite end engaging the free length of the skein 35 extending between the supports, and resilient means to swing the arm to apply pressure against the strands of the skein.

4. In a skein-unwinding device, the combination with rotatable means for supporting the skein, of a controller-arm pivoted 40 adjacent said means and arranged to be operated by the tension of the delivering yarn, said arm formed with a fork at one end adapted to inclose the strands of the skein 45 and to apply pressure thereto in accordance with variations in the tension of draft on the yarn.

5. In a skein-unwinding device, the combination with a pair of rotatable reels 50 adapted to support a skein extending around them, of an arm pivoted adjacent one of said reels and arranged with the yarn leading through a guide at one end, said arm having means at its opposite end adapted to bear on the inside of the skein, and means to swing said arm to apply pressure against the skein.

6. In a skein-unwinding device, the combination with a pair of rotatable reels adapted 60 to support a skein stretched between them, of a pivoted arm arranged to be operated by the yarn drawing off from the skein, said arm having a fork reaching under and in-

closing the strands of the skein extending between the reels on one side, and a spring 65 to swing the arm to apply pressure on the skein.

7. In a skein-unwinding device, the combination with rotatable reels for supporting a skein stretched between them, of a pivoted controller-arm constructed of wire bent at one end to form a pigtail and having its opposite end bent in a fork adapted to reach under and inclose the strands of the skein, the cross-bar of said fork being of substantially V-shape to adapt it to gather and straighten the strands, and means to rock the arm to press the fork into contact with the skein.

8. In a skein-unwinding device, the combination with a rotatable reel, of an arm pivoted on the axis of said reel and arranged to be longitudinally adjusted in relation thereto, said arm carrying a yarn-guide at one end and means adapted to engage the 85 strands of the skein at its opposite end.

9. In a skein-unwinding device, the combination with a rotatable reel, of means for supporting a controller device pivoted on the axis of said reel, and an arm secured to said 90 means to adapt it to be longitudinally adjustable therein, said arm carrying a yarn-guide at one end and means adapted to engage the strands of the skein at its opposite site end.

10. In a skein-unwinding device, the combination with reels for supporting the skein, of an arm pivoted on the axis of one of the reels, said arm formed with a yarn-guide at one end and a fork at the opposite end 100 adapted to engage the strands of the skein, a member adjustable in relation to the axis of the reel, a spring secured at one end to said member, and means for securing the opposite end of the spring to the arm to adapt it to be adjusted along the latter.

11. In a skein-unwinding device, the combination with brackets G, G', of bushings H arranged to be adjusted rotatively in said brackets, horizontal rods F, F' mounted in 11 said bushings, arms J, J' secured to said rods, a reel K rotatably mounted on the arm J, an arm N pivoted on the axis of said reel and adapted to engage the strands of the skein, an arm T pivoted at the end of 11 the arm J', a reel K' rotatably mounted at one end of the arm T, and a counterweight V adjustable along said arm.

12. In a skein-unwinding device, the combination with two horizontal rods, of means 1 to support said rods to allow them to be adjusted about their axes, arms J, J' fixedly secured to said rods, a reel K rotatably mounted on the arm J, an arm N pivoted on the axis of said reel and arranged with 1 one end adapted to engage the strands of

the skein, a bearing U pivoted on the arm J', an arm T longitudinally adjustable in said bearing, and a reel K' rotatably mounted on the arm T.

- 5 13. In a skein-unwinding device, the combination with an arm J', of a member U pivoted on said arm and formed with a bearing u', a split bushing u² in said bearing formed with a radial hole u⁵, a set-screw in
9 the bearing u' formed with a reduced end u⁴

engaging the hole u⁵, an arm T adjustable in the bushing u² and adapted to be clamped therein, and a reel K' rotatable on the arm T.

In testimony whereof I affix my signature in presence of two witnesses.

THOMAS J. SANDS.
